[57] CLAIM

The ornamental design for an ice cream freezer merchandiser, as shown and described.

DESCRIPTION

FIG. 1 is a top left side perspective view of an ice cream freezer merchandiser showing the design;
FIG. 2 is a left side elevational view thereof;
FIG. 3 is a right side elevational view thereof;
FIG. 4 is a top plan view thereof;
FIG. 5 is a bottom plan view thereof;
FIG. 6 is a front elevational view thereof; and,
FIG. 7 is a rear elevational view thereof.

The broken lines showing the wheels, boxes for the wheels, and the handles in FIGS. 1-7 are for illustrative purposes only and form no part of the claimed design.
